DOUBLE-DUTY CLOTHESLINE

Benjamin Goldman, New York, N. Y.

Application June 14, 1944, Serial No. 540,189

3 Claims. (Cl. 211—119.03)

This invention relates to new and useful improvements in clothes lines, and has more particular reference to a double duty clothes line.

More specifically, the invention proposes a new and improved double duty clothes line which is characterized by a pair of spaced pulleys and an endless heavy line mounted around the wheels of the pulleys. A lighter line is disposed beneath the heavy line and is supported by a plurality of strands adjustably connected with the heavy line for supporting the light line at selected elevated positions.

With this improved arrangement it is possible to support the clothes on the lighter line with clothes pins and the like. Since the lighter line does not engage around the pulleys it will remain cleaner for a longer period of time. Furthermore, it will not be exposed to heavy wear.

Another object of the invention is the construction of a device as mentioned which is simple and durable and which may be manufactured and sold at a reasonable cost.

For further comprehension of the invention, and of the objects and advantages thereof, reference will be had to the following description and accompanying drawings, and to the appended claims in which the various novel features of the invention are more particularly set forth.

In the accompanying drawings forming a material part of this disclosure—

Fig. 1 is a side elevational view of a double duty clothes line constructed in accordance with this invention.

Fig. 2 is a fragmentary enlarged plan view of Fig. 1.

Fig. 3 is an elevational view of Fig. 2.

Fig. 4 is a fragmentary transverse sectional view taken on the line 4—4 of Fig. 3.

Fig. 5 is a fragmentary vertical sectional view taken on the line 5—5 of Fig. 2.

Fig. 6 is an enlarged detailed view of a portion of Fig. 5.

Fig. 7 is a fragmentary sectional view similar to Fig. 4 but illustrating a modified construction.

The double duty clothes line, in accordance with this invention, includes a pair of spaced pulleys 10 and 11. An endless heavy line 12 is mounted around the wheels of the said pulleys 10 and 11. A lighter line 13 is disposed beneath the heavy line 12 and is supported by a plurality of strands 14. These strands 14 are connected with adjustable means on the heavy line 12 by which the lighter line 13 may be supported in various elevated positions.

The pulley 10 comprises a block or frame 15 sup-

porting a pair of adjacent wheels 16 and 17. The heavy line 12 engages around the wheel 16 so that one side engages between the wheels 16 and 17. A bracket 18 is connected with the block or frame 15 and is connected with a wash pole 19 or other support. The pulley 11 comprises a block or frame 20 supporting the wheels 21 and 22. The heavy line 12 engages around the wheel 21 and one side engages between the wheels 21 and 22. A bracket 23 connects with the block or frame 20 and is attached to a window frame 24 or other support. The wheel 21 is provided with a crank or handle 25 by which it may be manually turned.

Each strand 14 passes through a short vertical tube 26 fixedly mounted diametrically through the heavy line 12. Each tube 26 supports a casing 27 in which a drum 28 is rotatively mounted. The drum 28 is provided with a shaft 29 having an extended end provided with a handle 30 by which the drum may be turned. The handle 30 is equipped with a locking screw 31 by which the drum 28 may be locked in various positions by the screw 31 engaging a threaded opening 38 in the end of casing 27. The strand 14 is wound around the drum 28. When the set screw 31 is loosened the handle 30 may be turned for winding up or letting out the strand 14. In this way the various strands may be extended, or drawn in to lower or raise the lighter line 13. The frame or casing 30 of the pulleys are provided with raised portions 33 beneath which the casings 27 may pass. The adjacent wheels of each pulley frictionally engage and grip the heavy line 12.

In Fig. 7 a modified form of the invention is disclosed which is very similar to the prior form, distinguishing merely in the fact that the pulley 21 instead of being provided with a crank or handle by which it may be turned, is connected up with an electric motor 35 by which it may be electrically driven. In other respects this form of the invention is identical to the previous form and like parts are indicated by like reference numerals.

The use of the clothes line may be understood by an examination of Fig. 1. Clothes, indicated by reference character C, are attached to the light line 13 with clothes pins or other fastening elements. It should be noted that the light line 13 does not extend around any pulleys. It is merely by the strands 14.

While I have illustrated and described the preferred embodiments of my invention, it is to be understood that I do not limit myself to the precise constructions herein disclosed and the right is reserved to all changes and modifications com-

ing within the scope of the invention as defined in the appended claims.

Having thus described my invention, what I claim as new and desire to secure by United States Letters Patent is:

1. A double duty clothes line, comprising a pair of spaced pulleys, an endless heavy line mounted around the wheels of said pulleys, a lighter line beneath said heavy line, a plurality of strands for supporting said lighter line, and means for adjustably connecting said strands with said heavy line for supporting said lighter line at selected positions, comprising tubes mounted through said heavy line, casings on said tubes, drums rotatively mounted in said casings, said strands extending through said tubes and around said drums, and means for locking said drums in various turned positions.

2. A double duty clothes line, comprising a pair of spaced pulleys, an endless heavy line mounted around the wheels of said pulleys, a lighter line beneath said heavy line, a plurality of strands for supporting said lighter line, and means for adjustably connecting said strands with said heavy line for supporting said lighter line at selected positions, comprising tubes mounted through said heavy line, casings on said tubes, drums rotatively mounted in said casings, said strands extending through said tubes and around said drums, and means for locking said drums in various turned position, comprising shafts rotatively supported in said casings and having said

drums securely mounted thereon and having one of their ends extended from said casings, handles on the extended ends of said shafts by which said shafts may be turned for winding and unwinding said strands, and means for holding said handles against turning.

3. A double duty clothes line, comprising a pair of spaced pulleys, an endless heavy line mounted around the wheels of said pulleys, a lighter line beneath said heavy line, a plurality of strands for supporting said lighter line, and means for adjustably connecting said strands with said heavy line for supporting said lighter line at selected positions, comprising tubes mounted through said heavy line, casings on said tubes, drums rotatively mounted in said casings, said strands extending through said tubes and around said drums, and means for locking said drums in various turned position, comprising shafts rotatively supported in said casings and having said drums securely mounted thereon and having one of their ends extended from said casings, handles on the extended ends of said shafts by which said shafts may be turned for winding and unwinding said strands, and means for holding said handles against turning, comprising a set screw threadedly engaged through said handle and selectively threadedly engageable with one of a plurality of complementary threaded openings formed in the adjacent end of said casing.

BENJAMIN GOLDMAN.
